L. A. VANDIVER

COIN CONTROLLED MECHANISM FOR VENDING MACHINES

Filed June 28, 1926

UNITED STATES PATENT OFFICE.

LESLIE A. VANDIVER, OF KANSAS CITY, MISSOURI.

COIN-CONTROLLED MECHANISM FOR VENDING MACHINES.

Application filed June 28, 1926. Serial No. 119,009.

This invention relates to coin-controlled lock mechanism for vending machines of the general character exemplified by my Patent 970,280, issued September 13, 1910, my special object in this connection being to provide a construction involving the use of a manually-operable shaft for one or a battery of vending machines, and cooperating and forming in conjunction with a set screw or a plurality of set screws, a micrometer gage or gages insuring commodity-delivery operation of any particular one or more of the vending machines into which deposit was made of a proper coin or coins.

With this general object in view and others of a secondary or tributary character, the invention consists in certain novel and useful features of construction and combinations of parts as hereinafter described and claimed; and in order that it may be fully understood, reference is to be had to the accompanying drawing, in which:—

Figure 1 is a fragmental perspective view of a vending machine of convenient form for the application and use of mechanism embodying the invention.

Figure 2 is a vertical section taken substantially on the line II—II of Figure 3.

Figure 3 is a horizontal section on the line III—III of Figure 2, but omitting the coin chute appearing in the last-named figure.

Figure 4 is a vertical section, corresponding to Figure 3, but omitting certain parts of the latter, and showing other parts in a different position of adjustment.

Figure 5 is an enlarged fragmental view of part of the mechanism as it appears in Figure 3, but with certain parts thereof broken away.

Figure 6 is an elevation of part of a shaft which may be common to a plurality of vending machines.

Figure 7 is an enlarged vertical section on the line VII—VII of Figure 1.

Referring now to the drawing in detail, 1 is the body portion of a vending machine, and 2 a portion for the storage of packages of a commodity to be delivered, the commodity being delivered one package at a time into the body portion, and extricated

therefrom through an opening controlled by a door 3, shown in this instance as a pendently hinged door.

A shaft 4 extends horizontally across the body portion, and if the machine is in the form of a battery, the shaft will extend across the body portion of all members of the battery, and is operable by a crank handle 5 or the like, the limit of movement being between stop pins 6 and 7 or equivalent devices. Located in the body portion is a fixed horizontal guide or bracket 8 through which said shaft extends, the shaft having a notch or kerf 9 in the same longitudinal plane as an adjusting screw 10 also mounted in the bracket, adjustment of the screw toward or from the shaft determining the diameter or size of the coin selected for the operation of the device, the bracket having a slot 11 in the vertical plane of said screw and notch or kerf through which coins deposited in the machine are adapted to enter and lodge upon the shaft and screw when the shaft is so turned that its notch is not accessible to the coin, this being the initial or normal position.

Each coin is delivered into bracket slot 11 by a coin chute 12, within the body portion. A vertical coin chute 13 mounted upon the body portion and projecting thereinto and communicating with chute 12, has an opening 14 into which the coin is thrust or fed, the opening being preferably but not necessarily of size to exclude coins larger than that selected for the operation of the machine. To make it impracticable for the ready operation of the machine by a washer or other perforated disk, a pin 15 projects into the opening of the chute 13 and is adapted to be repressed by a solid coin and enter a perforated one to prevent the ready slippage of the latter down the chute. A closed sleeve 16 houses said pin, and a spring 17 normally holds it advanced as shown in Figure 7.

Rotatably mounted on shaft 4 is a wheel 18 provided with a peripheral package-receiving recess or pocket 19. With the type of vending machine shown, the packages for delivery will be of greater depth than

said recess or pocket but of size to fit snugly therein, the packages being arranged or stacked vertically so that the bottom one will occupy the pocket and be fed forwardly and dumped therefrom by sufficient rotation of said wheel in the direction indicated by the adjacent arrows, the package next to the bottom resting upon the peripheral portion of the wheel so that as the latter returns to its initial position the next package will fall into the pocket, it being understood however, as far as this application is concerned, the special type of vending machine is unimportant other than in the use of a rotary or oscillatory wheel or equivalent device, provided with a package-receiving and discharging pocket.

A retractile spring 20 is connected at one end to a fixed point such as a rod 21, and at its other end as at 22 to the wheel for the purpose of returning the latter to normal position, as shown in Figure 2, after each delivery operation, it being noted that a pin 23 projecting from the wheel and engaging the underside of the chute 12, limits backward rotation of the wheel.

At one side of wheel 18 and adjacent bracket 8, is a disk 24 having its hub secured rigidly on shaft 4 by a screw 25 or the like. A cross pin 26 is journaled in said disk and an arm 27 is rigidly secured to one end of said pin. An arcuate arm 28 is rigidly secured to the other end of said pin, the arrangement being such that said arms shall swing together in pivotal relation to the disk and at the same time be movable bodily by rotation of the latter. A retractile spring 29 connects the free end of arm 27 with the rod 21, and said arm is provided with a shoulder 30 for the purpose of engaging a laterally-projecting shoulder or pin 31 of wheel 18, to impart rotary movement to said wheel in a direction hereinafter mentioned. The arm 28 has a laterally-projecting pin 32, and a spring 33 fitted around the hub of arm 28 and fastened at its opposite ends to disk 24 and pin 32 tends to cause said pin when the disk is rotated, to ride forward on the guide bracket 8 over the slot 11 thereof, it being noted that if a coin C occupies said slot, it will cause the pin to ride upwardly over it and therefore rotate or pivotally operate upwardly the said arms 27 and 32 as the disk is turned. Through this upward pivotal operation the shoulder 30 of arm 27 is brought into engagement with the shoulder on pin 31 of the wheel and thus causes the latter to rotate forwardly with the disk and deliver the bottom-most package at a point from which it can be extracted by the purchaser, the operation being effected through the operation of the crank handle. When the pull on the crank handle is removed or sufficiently relaxed, the springs 20 and 29 tensioned in the previous operation,

return the wheel and disk to their initial positions.

If there is a battery of these vending machines having a common shaft 4, the shaft will have a notch 9 in the vertical plane of each screw 10 and slot 11, and the rotation of the shaft will bring the notch or notches into registration with the coin or coins just before the delivery of the package is effected, so that the coin or coins shall drop into a suitable receptacle, not shown, but within the machine, it being important that the coin be dropped before the corresponding package so that one cannot operate the device and obtain the delivery of more than one package from a single coin.

From the above description, it will be apparent that I have produced a machine embodying the features of advantage set forth as desirable in the statement of the object of the invention, and which may be modified in various particulars without departing from the spirit and scope of the appended claims.

I claim:

1. The combination with a rotary shaft, a package delivery device having a shoulder, a disk mounted to turn with the shaft, a coin chute and means cooperating with the perimeter of the shaft for intercepting and supporting a proper coin, of a slotted guide for the supported coin, a pair of arms pivoted to the disk, one having a pin to ride on the said guide and be pivotally raised by a coin when the same is supported by the shaft and said means, and the other a shoulder for engaging the shoulder of said delivery device when the shaft is turned; the shaft having a notch to register with the coin to permit the same to drop before the turning movement of the shaft has ended. 105

2. The combination with a rotary shaft, a package delivery device having a shoulder, a disk mounted to turn with the shaft, a coin chute and means cooperating with the perimeter of the shaft for intercepting and supporting a proper coin, of a slotted guide for the supported coin, a pair of arms pivoted to the disk, one having a pin to ride on the said guide and be pivotally raised by a coin when the same is supported by the shaft and said means, and the other a shoulder for engaging the shoulder of said delivery device when the shaft is turned; the shaft having a notch to register with the coin to permit the same to drop before the turning movement of the shaft has ended, means for returning the package delivery device to initial position after the coin is dropped, and means to return the shaft and disk to initial position when the operative force on the shaft is removed. 115

3. In a device of the character described, a shaft having an operating means, a wheel journaled on the shaft and provided with a peripheral pocket and a shoulder, a coin 120

guide over the shaft and provided with a guide slot, a pointed screw adjustable toward and from the shaft to co-operate with the latter in supporting a coin projected partly above the said guide, a disk rigid on the shaft, a pair of arms pivoted to the disk, one having a shoulder and the other a laterally-projecting arm, a spring for holding said arms depressed at their free ends so that the 10 pin of one as the shaft and disk are turned,

must ride over the projecting coin and be thereby raised to cause the shoulder of the other to engage the shoulder of the wheel to turn the same, the shaft having a notch to register with the coin and permit it to drop, 15 and independent means to return the shaft and wheel to their initial position.

In witness whereof I hereunto affix my signature.

LESLIE A. VANDIVER.
